United States Patent Office

Des. 178,462
Patented Aug. 7, 1956

178,462

PUFFED TEXTILE FABRIC

Douglas D. McCord, New York, N. Y., and Charles A. Rudolph, Cornelia, Ga., assignors to Chicopee Mills, Inc., a corporation of New York

Application June 20, 1955, Serial No. 36,598

Term of patent 14 years

(Cl. D92—1)

FIG. 1

FIG. 2

Fig. 1 is a plan view of a puffed textile fabric showing our new design; and Fig. 2 is an edge view of Fig. 1. We claim:

The ornamental design for a puffed textile fabric, as shown.
